UNITED STATES PATENT OFFICE.

FRANK J. A. PERRY, OF LYNN, MASSACHUSETTS, ASSIGNOR OF ONE-THIRD
TO CHARLES H. WALDEN, OF LYNN, MASSACHUSETTS.

LACING-HOOK.

SPECIFICATION forming part of Letters Patent No. 690,993, dated January 14, 1902.

Application filed May 2, 1901. Serial No. 58,445. (No model.)

To all whom it may concern:

Be it known that I, FRANK JOHN ALBERT PERRY, a subject of the King of Great Britain, residing at Lynn, in the county of Essex and 5 State of Massachusetts, have invented certain new and useful Improvements in Lacing-Hooks for Wearing-Apparel, of which the following is a specification.

This invention relates to lacing-hooks for 10 wearing-apparel, and is especially designed to be used on ladies' shoes, gloves, and similar articles of apparel, and has for its object to provide lacing-hooks of novel construction by means of which the lace may be conveniently, easily, and rapidly laced and unlaced, 15 which will not catch, become entangled in, or wear the clothing or the trimmings or fringes thereon, in which the ends of the hooks will be entirely covered by the lace, and which will 20 not abrade the apparel or be a source of discomfort to the wearer.

To these ends my invention consists in the 25 novel lacing-hook constructed and arranged in the manner hereinafter described, and particularly pointed out in the claims following the description, reference being had to the accompanying drawings, forming a part of this specification, wherein—

Figure 1 is a perspective view showing my 30 improved lacing-hooks applied to the shoe. Fig. 2 is a view, on an enlarged scale, showing one of the hooks applied to a shoe. Fig. 3 is a view in side elevation of the hook. Fig. 4 is a similar view looking from the other side 35 of the hook. Fig. 5 is a perspective view of one of the hooks. Fig. 6 is a view showing the hook attached to the shoe or article of apparel so as to project beyond the edge of the latter. Fig. 7 is a view in side elevation of 40 the hook shown in Fig. 6. Fig. 8 is a view of the blank from which the hook is made.

In forming my improved hook a blank of the shape shown in Fig. 8 of the drawings is 45 cut or stamped out from a piece of sheet metal or other suitable material. Said blank comprises a flat and relatively broad head 1, from one side or end of which projects a shank 2. In the example shown integral prongs 3 project from the opposite side or end of the head, 50 which are afterward bent at right angles to the head to serve as a convenient means for

attaching the lacing-hook to the shoe. I do not confine myself to the use of said prongs for attaching the lacing-hook to the shoe, as other well-known or preferred means for the 55 purpose may be employed. After the blank has been formed in the manner described the end of the shank 2 is bent, curved, or turned under to form the hook-bill 4, said hook-bill being bent or deflected to one side from under 60 the shank. The shank 2 of the hook is then given a slight torsional twist or quarter-turn, the twist being formed in a direction toward the side on which the hook-bill projects. It will be noted that one side of the shank 2 is 65 perfectly straight throughout its length, as at 5, while the outer end or corner of the other side thereof is cut away or removed, as at 6, to form a bevel or incline.

In applying the hooks to the slit portion of 70 the upper they are arranged at an angle to the edges of the slit, the shanks being inclined upwardly toward said edges at an angle of approximately forty-five degrees. When the hooks have been applied to the 75 shoe in the manner described, the shanks of each oppositely-arranged pair of hooks will project angularly upward toward one another, as shown in Fig. 1, said shanks being inclined upward or outward from the head 1, as most 80 clearly shown in Fig. 4, which arrangement renders the hooks most easily and conveniently engaged by the lace. By torsionally twisting the shank in the manner described the beveled corner or side of the bill-hook is 85 caused to lie next to the shoe-upper, and said beveled corner, in connection with the adjacent or underlying portion of the upper, forms a gradually-contracted or narrowed throat-way into which the lace can be readily and 90 quickly guided and through which the lace can be most easily slipped. Moreover, by beveling the corner or side of the hook-bill in the manner referred to an abrupt edge or projection is avoided which would otherwise 95 have a tendency to abrade or wear the leather and produce an uncomfortable pressure on the foot of the wearer. By bending the hook-bill laterally or to one side from beneath the shank the lace after it has been slipped beneath the hook-bill naturally and of itself 100 slips over said laterally-projecting bill and

between the latter and the shank, and in addition thereto after the shoe has been laced up the lace completely covers the ends of the hook-bills and prevents the latter from catching or becoming entangled in the edge of the skirt or the trimming thereon or from tearing or fraying the same.

In Figs. 1, 2, 3, and 4 I have shown the lacing-hooks so applied or secured to the shoe that the ends of the hooks do not quite reach to the edges of the slit in the upper, and this is the preferred arrangement, especially for shoes; but in Figs. 6 and 7 I have shown the hooks secured in place in such manner that the bill-hooks project beyond the edge of the article of apparel to which they are attached, this being desirable in some styles of garments.

It will be noted that it necessarily results from laterally bending the hook-bills to one side beneath the shanks and torsionally twisting the latter in the manner described that the lacing-hooks be made "rights and lefts," or, in other words, one set of hooks must be made for application to one side of the upper and a reversely bent and twisted set of hooks for the other side of the upper, and this is of advantage in that it insures each hook being so set that in the operation of lacing the shoe the lace readily, easily, and naturally slips into place in the hooks without care or pains being exercised on the part of the wearer.

To lace the shoe, it is merely necessary to slip the lace beneath the end of the hook and give it a very slight downward and outward pull, whereupon, owing to the beveled edge or corner of the hook-bill forming the gradually-constructed throatway, in the manner described, the lace will most readily and easily slip under the hook-bill, and as the lace is carried over to the other side of the shoe to engage the next lacing-hook it will, owing to the hook-bill being bent or deflected to one side, as shown, slip over the hook-bill and under the shank without any attention on the part of the one lacing the shoe whatsoever.

I have described the lacing-hook as being applied to a lady's shoe; but it will be obvious that it may be applied to all kinds of laced shoes and to various different kinds of wearing-apparel.

Having described my invention, what I claim is—

1. A lacing-hook comprising a head provided with means for its attachment to the article to be laced and provided at one side with a

rigid shank formed integral with the head, said shank being arched above the plane of the head and terminating in an undeturned hook-bill bent laterally to one side from beneath the shank, the transverse plane of said arched portion of the shank being disposed at an angle to the head.

2. A lacing-hook comprising a head provided with means for its attachment to the article to be laced and provided at one side with a shank terminating in an undeturned hook-bill, said shank being torsionally twisted, whereby the hook-bill lies in a plane inclined relatively to the plane of the head, substantially as described.

3. A lacing-hook comprising a head having means for its attachment to the article to be laced and provided at one side with a shank terminating in an undeturned hook-bill bent laterally to one side from beneath the shank, said shank being torsionally twisted, substantially as described.

4. A lacing-hook comprising a head having means for its attachment to the article to be laced and provided at one side with a shank terminating in an undeturned hook-bill bent laterally to one side and inclined or beveled off at its under corner, said shank being torsionally twisted, substantially as described.

5. A lacing-hook comprising a head having means for its attachment to the article to be laced and provided at one side with an arched shank terminating in a flat undeturned hook-bill bent laterally to one side from beneath the shank, said shank being torsionally twisted in the direction toward which the hook-bill is laterally bent, substantially as described.

6. In combination with an article to be laced, a lacing-hook comprising a head attached to said article and provided at one side with an integral rigid shank arched above the plane of the head and terminating in an undeturned hook-bill bent laterally to one side from beneath the shank, said hook-bill lying in a plane inclined relatively to the plane of the head and having its under corner beveled off so that the said beveled end of the bill lies parallel with the surface of the article to which the head is attached.

In testimony whereof I have hereunto set my hand in presence of two subscribing witnesses.

FRANK J. A. PERRY.
